UNITED STATES PATENT OFFICE.

CHARLES SPIRO, OF NEW YORK, N. Y.

PENCIL-SHARPENER.

No. 876,744.

Specification of Letters Patent.

Patented Jan. 14, 1908.

Application filed September 25, 1907. Serial No. 394,471.

To all whom it may concern:

Be it known that I, CHARLES SPIRO, citizen of the United States, residing at New York, county of New York, and State of New York, have invented certain new and useful Improvements in Pencil-Sharpener, of which the following is a specification, reference being had thereto to the accompanying drawing.

10 This invention relates to a pencil sharpener, and particularly to a construction embodying a socket and fixed blade relative thereto.

15 The invention has for an object to provide a novel and improved construction of sharpener wherein a circular blade having a continuous cutting edge is disposed at an angle to the axis of the pencil holding socket so as to produce a shearing cut as the pencil is rotated in said socket.

20 A further object of the invention is to provide a plurality of sockets coöperating with the blade so that either the wood of the pencil may be cut away or only the lead as found 25 desirable.

Other and further objects and advantages of the invention will be hereinafter fully set forth and the novel features thereof defined by the appended claims.

30 In the drawing:—Figure 1 is a side elevation of the invention; Fig. 2 is an end elevation thereof; Fig. 3 is an elevation of the back; Fig. 4 is a vertical section on the line 4—4, Fig. 3; Fig. 5 is an end view at the opposite end from Fig. 2; Fig. 6 is a detail perspective of the cutter blade, and Fig. 7 is a section on the line 7—7, Fig. 1.

Like numerals refer to like parts in the several figures of the drawing.

40 Referring to the drawing, the numeral 10 designates the pencil receiving socket the aperture of which tapers gradually from one end to the other so as to form a point receiving opening 11 into which the lead of the pencil may extend for the purpose of protecting the same and also centering the pencil while cutting the wood therefrom. Disposed diagonally to the longitudinal axis of this socket is the supporting plate 12 provided with the 45 central aperture 13, preferably formed integral with the socket 10. Upon the upper surface of the socket 10 and at one side of the plate 12 is a point receiving socket 14 having a tapered interior in order to present the lead

of the pencil for sharpening. The upper portion of the socket 10 at the base of the plate 12 is cut away as shown at 15, this portion extending transversely of and diagonally to the longitudinal axis of the socket 10.

Upon the face of the plate 12 the cutter 55 blade 16 is mounted, this blade being of thin wafer steel and provided with a continuous circular cutting edge 17. This form of blade forms the most desirable cutting means and can be repeatedly sharpened in a convenient 60 manner. The blade is pivotally mounted at the central aperture 18 by means of the clamping screw 19 which passes therethrough and is threaded into the aperture 13 of the plate 12. This screw has a shoulder 70 20 bearing upon the blade so as to secure an extended contact for retaining the blade in its adjusted position. The adjustment of the blade may be effected in any desired manner when the screw is slightly loosened, 75 for instance, by means of inserting any object in the aperture 21 by which the blade may be rotated on the screw. For the purpose of determining the extent of this rotation and also the area of the surface which 80 has been previously used a series of radial graduations 22 are formed on the blade. It will be observed that the plate 12 and the blade carried thereby are disposed diagonally 85 to the longitudinal axis of the socket 10 and that the edge of the blade is presented to the pencil in a plane traversing the path of a cord of the pencil socket toward the direction of the travel of the pencil, while the circular edge of the blade extends diagonally across 90 the surface to be cut thus producing a shearing cut upon a diagonal line crossing the axis of the pencil transversely thereof.

In the use of the invention, the wood of the pencil is first cut away in the pencil 95 socket there being a clearance aperture to receive the lead which need not be cut at this time, and the danger of breaking the point owing to the difference in the cutting resistance between the wood and lead is 100 obviated and the full thickness of the point may be retained. After the wood is cut away to the proper extent the pencil is then inserted into the point socket and the point finished by a rotation against the periphery 105 of the blade. In this manner the wood may be cut away to the extent desired and the lead pointed as the point becomes worn off

without the necessity of again cutting the wood as the point can be sharpened very quickly by turning the pencil against the blade. As before stated, the disposition of this blade is such as to permit the cutting with least resistance and therefore avoids the breaking or splitting of the pencil, while the plate upon which the blade is mounted projects beyond the edge thereof for sufficient distance to protect the cutting edge of the blade. The use of a blade having a circular cutting edge permits its formation from wafer steel or other thin material which can be conveniently sharpened and replaced, and the entire periphery thereof can be used, the position or shift thereof necessary being indicated by the graduations thereon. This form of blade also permits the use of a plurality of sockets as before described adapted to contact at different points with a single cutting surface so that either the wood or lead of the pencil may be sharpened as found desirable. It will therefore be apparent that the invention presents a simple, economically constructed and efficient form of pencil sharpener in which the greatest length of surface for the blade may be secured.

Having described my invention and set forth its merits, what I claim and desire to secure by Letters Patent is:—

1. A pencil sharpener comprising a pencil socket having a supporting plate extended therefrom, and a blade having a circular cutting edge disposed at an angle to the longitudinal axis of said socket.

2. A pencil sharpener comprising a pencil socket having a supporting plate extended therefrom, and a blade having a circular cutting edge disposed at an angle extending diagonally to the longitudinal axis of said socket.

3. A pencil sharpener comprising a pencil socket having a supporting plate extended therefrom, and a blade having a circular cutting edge disposed at an angle to the longitudinal axis of said socket and in a plane traversing the path of a cord thereof.

4. A pencil sharpener comprising a pencil socket provided with a supporting plate disposed diagonally to the longitudinal axis thereof, a blade having a continuous circular cutting edge pivotally mounted upon said plate, and means for retaining said blade in adjusted position.

5. In a pencil sharpener, a pencil socket, a supporting plate extended therefrom, a blade having a continuous circular cutting edge mounted upon said plate, and a clamping screw extending through said blade and threaded into said plate.

6. In a pencil sharpener, a pencil socket, a supporting plate extended therefrom, a blade having radial graduations thereon and a continuous circular cutting edge mounted upon said plate, and a clamping screw ex-

tending through the blade and threaded into said plate.

7. In a pencil sharpener, a pencil socket, a supporting plate extended therefrom, a blade having an adjusting aperture and radial graduations and provided with a continuous circular cutting edge mounted upon said plate, and a clamping screw extending through the blade and threaded into said plate.

8. In a pencil sharpener, a pencil socket, a supporting plate extended therefrom, a curved blade mounted upon said plate, and a point socket disposed adjacent to said blade.

9. In a pencil sharpener, a pencil socket, a supporting plate extended therefrom, a circular blade mounted upon said plate, and a point socket disposed between one end of the pencil socket and the periphery of said blade.

10. In a pencil sharpener, a pencil socket, a supporting plate extended therefrom, a circular blade mounted upon said plate, a point socket disposed between one end of said pencil socket and the periphery of said blade, and a clamping screw threaded into said plate and having a shoulder to engage the surface of said blade.

11. In a pencil sharpener, a pencil socket provided at one end with a point receiving aperture, a supporting plate extended from said socket, a blade mounted upon said plate and having a continuous circular cutting edge, and means for permitting rotative adjustment of said blade.

12. In a pencil sharpener, a pencil socket provided with an aperture in its upper face, a supporting plate carried by said socket, and a blade having a curved cutting edge disposed at said aperture and extending diagonally to the longitudinal axis of said socket.

13. In a pencil sharpener, a pencil socket provided with an aperture in its upper face, a supporting plate carried by said socket, a blade having a curved cutting edge disposed at said aperture and extending diagonally to the longitudinal axis of said socket, and a point socket disposed tangentially to said curved blade.

14. A pencil sharpener comprising a body portion having a pencil socket, a supporting plate extended diagonally to the longitudinal axis of said socket with a point socket interposed between the rear end of the pencil socket and the periphery of said plate, and a circular blade mounted upon said plate.

15. In a pencil sharpener, a supporting frame provided with a pencil socket and a point socket in combination with a rotatable adjustable blade in cutting relation with both sockets.

16. In a pencil sharpener, a supporting frame, a blade mounted thereon, and independent pencil and point sockets each having their line of introduction for the pencil

and point at the same angle relative to a single cutting edge of the blade.

17. In a pencil sharpener, a frame provided with a pencil socket and a point socket, 5 and a blade mounted in said frame having a single cutting edge disposed in cutting relation to both sockets.

In testimony whereof I affix my signature in presence of two witnesses.
